UNITED STATES PATENT OFFICE.

EDGAR C. GNAU, OF EAST AURORA, NEW YORK.

CONNECTION PROTECTOR.

Application filed December 3, 1921. Serial No. 519,729.

To all whom it may concern:

Be it known that I, EDGAR C. GNAU, a citizen of the United States, residing at East Aurora, in the county of Erie and State of New York, have invented a new and useful Connection Protector, of which the following is a specification.

This invention has reference to electric wire connections, and more particularly to a protector designed to shield the connection between electric wires, to eliminate any possibility of short circuiting or grounding the circuit.

An object of the invention is to provide a shield or protector which may be readily and easily applied and one which will not interfere with the splicing or connecting of wires.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of the protector.

Figure 2 is a front elevational view of the same.

Figure 3 is an elevational view of the upper section of the protector.

Figure 4 is an elevational view of the lower section thereof.

Referring to the drawing in detail, the connector embodies an upper section 5 which is formed with a wire gripping section 5' designed to be bent around a wire and secured in such position, as by means of the bolt 6, which passes through registering openings in the section 5'.

The upper section also includes a downwardly extending portion 7 which has one end formed into a sleeve 8 adapted to accommodate a wire to be secured to the connector. A bolt 9 extends through the portion 7 at a point directly above the sleeve

8, whereupon the wire may be secured to the connector in a manner to prevent displacement thereof.

Disposed substantially intermediate the ends of the connector is a cap 10 which is secured to the body portion of the connector in any suitable manner, and is formed with inwardly extending lugs 11. These lugs 11 are disposed in spaced relation with the body portion of the connector to provide a clearance for the lower section 12 of the protector. The lower section 12 is bell-shaped, as clearly shown by Figure 4 of the drawing, and is formed with a reduced portion 13 providing a shoulder 14 at the base thereof, which shoulder abuts the lower end of the cap 10 to restrict movement of the bell-shaped portion 12, with respect to the cap.

Formed within the reduced portion 13 and disposed at opposite sides thereof, are the slots 14' which communicate with the grooves 15 formed in spaced relation with the shoulder 14 and extends slightly downwardly.

From the foregoing it will be seen that the lower section 12 of the protector may be secured to the upper section by moving the lower section to bring the slots 14' to positions to receive the lugs 11. The lower section 12 may be forced upwardly and twisted slightly, to lock the lower section 12 to the cap 10.

In this position, a protector is formed for the connection between the connector proper and the wire 16, which is shown in dotted lines in Figure 3 of the drawing, to the end that all moisture or rain is excluded from the connection.

Having thus described the invention, what I claim as new is:

A shield for electric connections including a supporting wire, an upper section including a length of metal having one end thereof bent upon itself to grip the supporting wire, a cap forming a part of the upper section, the length of metal extending below the lower edge of the cap and having its lower extremity bent to grip a wire to secure the wire to the length of 100

metal, a bell-shaped lower section having bayonet slots formed at a point adjacent to the upper end thereof, lugs extending inwardly from the cap and adapted to move into the slots for securing the lower section to the cap, the lower section having a shoulder engaging the lower edge of the cap to restrict movement of the lower section, and said lower section having an upper re-

duced extremity adapted to fit into the cap to provide a fluid-tight connection.

In testimony that I claim the foregoing as my own, I have hereto affixed my signature in the presence of two witnesses.

EDGAR C. GNAU.

Witnesses:

EDW. BARTLETT,
BERNARD L. WAHL.
